REFRIGERATION APPARATUS AND METHOD

William B. Anderson, West Springfield, and Graham S. McCloy, East Longmeadow, Mass., assignors to Westinghouse Electric & Manufacturing Company, East Pittsburgh, Pa., a corporation of Pennsylvania

Application July 28, 1937, Serial No. 156,162

21 Claims. (Cl. 62—115)

Our invention relates to refrigeration apparatus and to a method for charging refrigeration apparatus with refrigerant and lubricant.

Before a closed refrigerating system is charged, it is necessary for several reasons to remove all non-condensable gases, such as, for example, air, from the refrigerating system. For example, the presence of non-condensable gases will cause high head pressures in the high side of the system so that the efficiency of the system will be reduced and, if large amounts of non-condensable gases are present, the machine may cease to operate. Furthermore, non-condensable gases and air in the system may cause oxidation and deterioration of the parts of the system. Again, in refrigerating systems where lubricant is present, the non-condensable gases and air sometimes react with the lubricant or refrigerant and form water, with the result that the water combines with other chemicals in the system and causes oxidation and rusting of the parts of the refrigerator. In hermetically sealed systems wherein the motor and compressor are contained within a sealed casing, the presence of non-condensable gases or air may form chemical combinations with the refrigerant and lubricant which deleteriously effect the insulation on the windings of the motor, etc. It is, therefore, necessary to completely evacuate all non-condensable gases from the system before it is placed in the field charged with liquid refrigerant and lubricant.

Heretofore, refrigerating systems have been charged with liquid refrigerant by first drying the refrigerating system with warm air or inert gas and then evacuating the system with high vacuum apparatus. The apparatus for performing the evacuation portion of the process is expensive, cumbersome, and necessarily slow in operation and, furthermore, it is very difficult to completely remove the non-condensable gases from the system. In addition, the refrigerant and lubricant with which the system is afterwards charged contain non-condensable gases which are not removed by prior evacuation.

It is an object of our invention, therefore, to provide improved apparatus and an improved method for removing non-condensable gases from a refrigerating system and for charging the system with refrigerant.

It is also an object of our invention to remove the non-condensable gases from the system by operation of the compressor of the refrigerating system and to thus dispense with expensive and cumbersome evacuating apparatus.

It is still a further object of our invention to

provide evacuating and charging apparatus which may be readily used in the field for servicing refrigerating systems.

It is still another object of our invention to provide an evacuating and charging system for refrigerating units which is particularly adaptable for use in systems in which a hermetically sealed motor compressor unit is utilized.

It is another object of our invention to provide a method of evacuating and charging a refrigerating system wherein the non-condensable gases which are contained in the refrigerant and lubricant charge are removed from the system.

It is still another object of our invention to provide apparatus for charging a refrigerating system with refrigerant which readily adapts itself to accurately charging the refrigerant by the weight thereof, which is considerably more accurate than charging by volume.

It is also an object of our invention to provide a charging system which is particularly adapted to large production methods and which may be used to evacuate and charge the refrigerating systems without removal from a moving conveyer assembly and test system and without stopping the conveyer.

These and other objects are effected by our invention, as will be apparent from the following description and claims taken in connection with the accompanying drawing, forming a part of this application, in which:

Fig. 1 of the drawing is a diagrammatic illustration of a refrigerating system embodying our invention; and

Fig. 2 is a view of a system similar to that shown in Fig. 1, but using a float valve flow restrictor instead of a capillary tube between the condenser and the evaporator.

Referring specifically to the drawing for a detailed description of our invention, numeral 11 designates a sealed casing in which is contained a reciprocating compressor 12 and a driving motor 13. Refrigerant is forced from the compressor 12 through a conduit 14 in a high pressure and superheated gaseous state to a condenser 15. The high pressure refrigerant gas is cooled in the condenser and condensed, a motor-driven fan 16 forcing cool air over the condenser for that purpose. In the system shown in Fig. 1, condensed refrigerant is conveyed through a conduit 17 to a tube 18 of considerable length and restricted diameter sometimes referred to as a "capillary tube". The capillary tube 18 feeds refrigerant into an evaporator 19 in which the refrigerant is vaporized and is drawn into the interior of the

sealed casing 11 through a conduit 21. Low pressure refrigerant vapor in the casing is drawn into the compressor through an inlet conduit 22 and the cycle is then repeated. It is, therefore, apparent that the interior of the sealed casing and the motor windings are subjected to the low pressure refrigerant gas.

In accordance with our invention as shown in Fig. 1, a combination purge valve and charging valve 23 is disposed in the conduit 14 extending between the compressor and the condenser. A threaded opening 24 in the valve 23 receives a threaded plug 25 which may be removed for purging the system. The valve 23 is provided with a standpipe 26 attached to an opening 27 in the valve by soldering or brazing. The upper end of the standpipe 26 is threaded as indicated at 28. An assembly consisting of a hand operated valve 29 and a closed container 31 communicating with the valve 29 is attachable to the threaded opening 28 by a threaded conduit 32 and a connecting fitting 30.

The refrigerating system is first subjected to a flow of warm dry air or inert gas, such as, for example, nitrogen, for a sufficient time to substantially remove the moisture from the system. After dehydration, the system, still filled with air or inert gas is placed on a conveyer (not shown) and is charged with the proper amount of lubricant through a conduit 20, which opens into the motor-compressor casing and which is pinched off and sealed after lubricant charging. During this time, the system is open to the atmosphere through the conduit 29 and through the standpipe 26, since the hand valve 29 and container 31 have not as yet been attached. The entire system is, however, above room temperature, having been heated by the warm drying gas, and very little, if any, air from outside the system will enter it.

At this time, the pressure throughout the system is substantially at atmospheric pressure. After the system has been charged with lubricant and the pipe 20 pinched off, the compressor is preferably operated for a short time, such as two minutes, with the result that partial evacuation of the low side of the system is effected. This operation is also known as auto-evacuation since it is effected by the operation of the system itself. The air or gas present in the low side of the system comprising mainly the evaporator 19 and the interior of the sealed casing 11 is exhausted to the atmosphere, for example, through the open end 28 of the standpipe 26. The pressure in the low side of the system is thus reduced to 25 inches of vacuum or lower. The pressure in the high side of the system, comprising mainly the condenser 15 and conduits 14 and 17, is still at atmospheric pressure because it is vented to the atmosphere through the open standpipe 26.

The high pressure side of the system is closed to atmosphere while the compressor is still operating. In the capillary tube type of refrigerating apparatus illustrated in Fig. 1, the screw fitting 30 is attached to the threaded ends of the standpipe 26 and conduit 32 while the compressor is still operating. Liquid refrigerant sufficient to charge the system is present in the container, and the hand valve is closed. This procedure is followed because if the compressor were stopped, air would again quickly leak into the low side of the system and negate the effect of the auto-evacuation which has just been completed. The pressure in the high side does not build up to any appreciable extent at this time because the low side is substantially evacuated and only small

quantities of gas are being pumped into the high side of the system.

At this time, the exact refrigerant charge by weight is within the container 31. While most of the refrigerant by weight is in liquid state in the container 31, some refrigerant gas is present in the container 31. Most refrigerants, such as sulphur dioxide or dichlorodifluoromethane, are at a higher pressure than atmospheric in the container 31 when subject to room temperatures. However, it is not necessary for successful utilization of our invention that the refrigerant pressure in the container 31 be above atmospheric at this time.

After the hand valve 29 and the refrigerant filled container 31 are attached to the standpipe 26, the compressor 12 is stopped by deenergizing the motor 13. The hand valve 29 is then opened and liquid refrigerant runs into the system by gravity, or by pressure difference and gravity if the pressure in the container 31 is above the pressure in the high side of the refrigerating system. The entire assembly is then tested for leaks, and if none are found, the compressor 12 is again started and runs continuously for approximately an hour. During this time, the compressor pumps a mixture of non-condensable gases and gaseous refrigerant into the conduit 14, both of which are forced into the container 31 on each stroke of the compressor. Since the container is disposed in the relatively cool ambient air, and the refrigerant gas is at high pressure, the refrigerant gas is condensed and returns to the system through hand valve 29, conduit 32 and standpipe 26, by gravity. The conduit 32 and standpipe 26 are of sufficient diameter that the condensed refrigerant on the one hand and the gaseous refrigerant and non-condensable gases on the other hand flow therethrough in counter-flow relation. The non-condensable gases delivered to the container 31 are not condensed and remain therein until, within a relatively short time, all the non-condensable gases remaining in the system after auto-evacuation are contained in the container 31, together with a small quantity of refrigerant gas. The hand valve 29 is then closed and the standpipe 26 is pinched off and immediately sealed. The hand valve 29 is then unscrewed from the threaded connection on the standpipe, and the hand valve 29 and container 31 are used on another refrigerating system for charging the same.

By first auto-evacuating the system of non-condensable gases, the size of the container 31 may be relatively small, it being sufficiently large, however, to contain the exact refrigerant charge required for the system. It will also be apparent that the container 31 is preferably disposed above the highest liquid level of the system, since it is connected into the high side of the system and it is desirable that condensed liquid refrigerant from the container 31 return to the system by gravity when the compressor 12 is operating. The complete evacuating and charging operation may be started and completed as soon as the system has been dried, and the system need not be removed from the conveyer at any time. The size of the container 31 may be considerably less than the sealed casing and obviously does not occupy much space above the conduit 14.

In the embodiment of our invention shown in Fig. 1, utilizing a capillary tube, non-condensable gases circulate through the system and are present in the conduit 14 and in the top of the condenser, and the container 31 is, therefore, con-

nected into the conduit 14. In the embodiment shown in Fig. 2, however, a refrigerating system utilizing a float valve 35 controls the flow of refrigerant from the high to the low side of the system. Like numerals designate the parts of compression system in Fig. 2 as in Fig. 1 with the exception of the float valve and the parts of the system used for charging. The float valve 35 comprises a tank 36 into which liquid refrigerant from the condenser 15 is discharged through conduit 37. A float ball 38 is hingedly supported at 40 within the tank 36 and operates a valve 39 including a needle plunger 41 which coacts with a valve seat 42. The valve 39 is, therefore, opened and closed in response to changes in liquid level in the tank 36. The tank 36 is also provided with a purge opening 43 closed by a threaded plug 44.

Since non-condensable gases collect in the top 20 of the float tank 36, in this embodiment of our invention, a container 45 for charging the system is connected to the top of the float tank 36 by a standpipe 46 welded or brazed to an opening 47 in the top of the float tank. The standpipe 46 25 is provided with a threaded upper end 48 to which a threaded conduit 49 is attached by a fitting 51. The conduit 49 is connected to a hand valve 52 which connects the float tank 36 with the container 45, when it is open. The container 45 is 30 disposed above the highest liquid level in the system, since it is also desirable in this embodiment of our invention to have the refrigerant liquid run into the system by gravity when the compressor (not shown) is operating.

The system shown in Fig. 2 is dried and charged 35 with liquid refrigerant by the same steps and in the same sequence described with respect to Fig. 1. Clearly, as the liquid refrigerant charge flows into the system, and as refrigerant gas is condensed, liquid refrigerant enters the float tank 36 and lifts the valve 39 so that the charge is properly distributed throughout the system. As the compressor 12 operates, a mixture of refrigerant gas and non-condensable gases are 40 forced into the container 45, whereupon the refrigerant gas condenses and returns to the system through hand valve 52, conduit 49 and standpipe 46, while the non-condensable gases remain in the container 45. After all the non-condensable gases are contained within the container 45, and the system has been charged, the standpipe 46 is pinched off and immediately sealed and the hand valve 52 and container 45 may be used on another system.

The method of removing the non-condensable 45 gases from a system which contains its refrigerant and lubricant charge is fully disclosed and claimed in the copending application of Graham S. McCloy, Serial No. 140,011, filed April 30, 1937, and assigned to the assignee of the present application.

From the foregoing, it will be apparent that we have provided an improved system and method for charging refrigerating units with refrigerant and lubricant, which system and method dispenses with expensive evacuating apparatus and is also adaptable for use in either the factory or in the field. While we have shown our invention as applied to a hermetically sealed compression refrigerating unit, it is obvious that our invention is applicable to many other forms of refrigerating systems.

While we have shown our invention in two forms, it will be obvious to those skilled in the art that it is not so limited, but is susceptible of

various other changes and modifications without departing from the spirit thereof, and we desire, therefore, that only such limitations shall be placed thereupon as are imposed by the prior art or as are specifically set forth in the appended claims.

What we claim is:

1. The method of charging a closed refrigerating system with a refrigerant, which system includes a compressor and initially contains gases which are non-condensable at ordinary temperatures, which method comprises connecting a container of refrigerant into the system, the quantity of refrigerant in said container at the time of connecting it being sufficient for charging the system, operating the compressor to force said non-condensable gases into said container and transferring said refrigerant from said container into the system.

2. The method of charging a closed refrigerating system with a refrigerant, which system includes a compressor and initially contains gases which are non-condensable at ordinary temperatures, which method comprises connecting a container in communication with the high pressure side of the system, supplying the container with a charge of refrigerant most of which, by weight, is in liquid state, and which is sufficient for a complete charge for the system, transferring liquid refrigerant from the container into the system, operating the compressor to force the non-condensable gases into the container, condensing gaseous refrigerant which enters the container from the system as the compressor operates, retaining the non-condensable gases in the container, continuing the operation of the compressor until the system is completely charged with refrigerant and substantially all the non-condensable gases are in the container and then isolating the system from said container.

3. The method claimed in claim 2 wherein the container is removed from the system and the system is sealed when substantially all the non-condensable gases have been transferred to the container.

4. The method of charging a closed refrigerating system with a refrigerant, said system including a compressor, a condenser, an evaporator and an open restriction for controlling the flow of refrigerant between the condenser and the evaporator and which system initially contains gases which are non-condensable at ordinary temperatures, which method comprises connecting a container in communication with the high pressure side of the system, supplying the container with a charge of refrigerant most of which, by weight, is in liquid state, and which is sufficient for a complete charge for the system, transferring liquid refrigerant into the system, operating the compressor to force the non-condensable gases into the container, condensing gaseous refrigerant which enters the container from the system as the compressor operates, retaining the non-condensable gases in the container, continuing the operation of the compressor until the system is completely charged with refrigerant and substantially all the non-condensable gases are in the container and then isolating the system from said container.

5. The method of charging a closed refrigerating system having high and low pressure sides with a refrigerant, said system including a motor-compressor unit which is enclosed by a hermetically-sealed casing normally containing refrigerant gas and which system initially contains gases

which are non-condensable at ordinary temperatures, which method comprises connecting a container in communication with the high pressure side of the system, supplying the container with a charge of refrigerant, transferring refrigerant into the system, operating the compressor to force the non-condensable gases into the container, condensing gaseous refrigerant which enters the container from the system as the compressor operates, retaining the non-condensable gases in the container and continuing the operation of the compressor until the system is completely charged with refrigerant and substantially all the non-condensable gases are in the container.

6. The method of charging a closed refrigerating system with refrigerant, said system including a compressor and initially containing gases which are non-condensable at ordinary temperatures and which system is divided into high and low pressure sides, which method comprises operating the compressor with the high pressure side open to the atmosphere to substantially exhaust the non-condensable gases from the low pressure side, connecting a container in communication with the high pressure side of the system, supplying the container with a charge of refrigerant, transferring refrigerant into the system, operating the compressor to force the non-condensable gases into the container, condensing gaseous refrigerant which enters the container from the system as the compressor operates, retaining the non-condensable gases in the container, continuing the operation of the compressor until the system is completely charged with refrigerant and substantially all the non-condensable gases are in the container and then isolating the system from said container.

7. The method of charging a closed refrigerating system with a refrigerant, which system includes a compressor and initially contains gases which are non-condensable at ordinary temperatures, and which system is divided into high and low pressure sides by a float controlled valve, which method comprises operating the compressor with the high pressure side of the system open to atmosphere to substantially exhaust the non-condensable gases from the low pressure side of the system, connecting a container in communication with the high pressure side of the system and disposing it above the portion of the system to which it is connected, supplying the container with a charge of refrigerant most of which is in the liquid state, transferring liquid refrigerant into the system, operating the compressor to force the non-condensable gases into the container, condensing gaseous refrigerant which enters the container from the system as the compressor operates, retaining the non-condensable gases in the container, continuing the operation of the compressor until the system is completely charged with refrigerant and substantially all the non-condensable gases are in the container and then isolating the system from said container.

8. In refrigerating apparatus in which a refrigerant is compressed, condensed and vaporized, the combination of a compressor, a condenser, an evaporator, a device for controlling the flow of refrigerant between the condenser and the evaporator, said compressor and condenser embodying a high pressure side of the system and said evaporator embodying a low pressure side of the system, and a container containing a complete charge of refrigerant for the system adapted

to be connected to the high pressure side of the system and so disposed that refrigerant will be transferred into the system, said container being adapted to collect the non-condensable gases present in the system and to retain the non-condensable gases therein.

9. In a refrigerating system in which a refrigerant is compressed, condensed and vaporized, the combination with a compressor, a condenser, an evaporator, a flow control device of relatively restricted diameter and considerable length disposed between the condenser and the evaporator, a conduit connecting the condenser with the compressor and container connected into and disposed above highest liquid level in the system, said container containing a complete charge of refrigerant for the refrigerating system so that the refrigerant will flow into the system, said container being adapted to collect the non-condensable gases present in the system when said compressor is operating and to retain the non-condensable gases therein.

10. In refrigerating apparatus in which a refrigerant is compressed, condensed and vaporized, the combination with a compressor, a condenser, an evaporator, a float controlled device disposed between the condenser and the evaporator, a container connected to said float control device in the high pressure portion thereof, said container containing a complete charge of refrigerant for the refrigerating system so that the refrigerant will flow into the system, said container being adapted to collect the non-condensable gases present in the system when said compressor is operating and to retain the non-condensable gases therein.

11. The method of effecting the exchange of refrigerant and non-condensable gases between a container and a refrigerating system having a compressor, which method includes charging a container with a predetermined quantity of refrigerant sufficient to completely charge the refrigerating system, establishing communication between the container and the refrigerating system and effecting the delivery of the refrigerant in the container to the refrigerating system, operating the compressor for circulating refrigerant and the non-condensable gases in the refrigerating system, collecting the non-condensable gases in the container and terminating communication between the container and the refrigerating system when substantially all of the non-condensable gases and refrigerant have been exchanged.

12. The method of charging and removing non-condensable gases from a refrigerating system having high and low pressure sides and including an evaporator, a compressor, a condenser, and an expansion device, which method comprises admitting to a container sufficient refrigerant for a complete refrigerant charge for the system, connecting the container with the refrigerant charge therein to the high-pressure side of the system, transferring the refrigerant charge from the container to the system, and transferring from the system to the container those non-condensable gases which are contained in the system at the time of transfer of the refrigerant charge into the system by operating the compressor to effect flow of a mixture of non-condensable gases and refrigerant vapor at substantially condenser pressure into the container, and condensing refrigerant vapor in the container and returning the condensed refrigerant to the system.

13. The method of charging and removing non-condensable gases from a refrigerating system including an evaporator, a compressor, a condenser, and an expansion device, which method comprises connecting a container containing refrigerant to the high pressure side of the system, transferring refrigerant from the container to the system, collecting in the container substantially all the non-condensable gases contained in the system at the time of transfer of refrigerant into the system by operating the compressor to effect flow of a mixture of non-condensable gases and refrigerant vapor at condenser pressure into the container and condensing refrigerant vapor in the container, the refrigerant condensed in the container being returned to the system, and then disconnecting the container from the system.

14. The method of charging and removing non-condensable gases from a refrigerating system, which method comprises admitting to a container only the quantity of refrigerant required for a complete refrigerant charge for the system, connecting the container with the refrigerant charge therein to the system, transferring the refrigerant charge from the container to the system, and transferring the non-condensable gases from the system to the container by operating the system to effect flow of a mixture of non-condensable gases and refrigerant vapor into the container.

15. The method of charging and removing non-condensable gases from a refrigerating system including an evaporator, a compressor, a condenser, and an expansion device, which method comprises admitting to a container the proper amount only of refrigerant required for a complete refrigerant charge for the system, connecting the container with the refrigerant charge therein to the high pressure side of the system and transferring the refrigerant charge to the system, and removing from the system the non-condensable gases contained therein at the time of transferring the refrigerant charge to the system by operating the compressor to effect flow of a mixture of non-condensable gases and refrigerant vapor at condenser pressure into a heat transfer device and condensing refrigerant vapor therein, the refrigerant condensed in the heat transfer device being returned to the system, and closing communication between the system and the container.

16. The method of charging and removing non-condensable gases from a refrigerating system including an evaporator, a compressor, a condenser, and an expansion device of a type which passes some gaseous fluid under some conditions of operation, which method comprises admitting to a container sufficient refrigerant for a complete refrigerant charge for the system, connecting the container with the refrigerant charge therein to the high pressure side of the system between the compressor discharge and the condenser inlet, transferring the refrigerant charge from the container to the system, transferring from the system to the container the non-condensable gases contained in the system at the time of transfer of the refrigerant charge into the system by operating the compressor to effect flow of a mixture of non-condensable gases and refrigerant vapor at condenser pressure into the container and condensing refrigerant vapor in the container, the refrigerant condensed in the container being returned to the system.

17. The method of charging and removing non-condensable gases from a refrigerating system including an evaporator, a compressor, a condenser, and an expansion device, which method comprises connecting a container containing refrigerant to the high pressure side of the system, transferring refrigerant from the container to the system, collecting in the container substantially all the non-condensable gases contained in the system at the time of transfer of refrigerant into the system by operating the compressor to effect flow of a mixture of non-condensable gases and refrigerant vapor at condenser pressure into the container and condensing refrigerant vapor in the container, the refrigerant condensed in the container being returned to the system, and then disconnecting the container from the system.

18. The method of charging and removing non-condensable gases from a refrigerating system including a compressor, which method comprises operating the compressor to exhaust a substantial quantity of non-condensable gases from the low-pressure side of the system to the high-pressure side and venting non-condensable gases from the high-pressure side, admitting a refrigerant charge to the system, providing a container connected to the system, transferring from the system to the container the non-condensable gases contained in the system at the time of admitting the refrigerant charge thereto by operating the compressor to effect flow of a mixture of non-condensable gases and refrigerant vapor into the container and condensing refrigerant vapor in the container, and returning the refrigerant condensed in the container to the system.

19. The method of charging and removing non-condensable gases from a refrigerating system including a compressor, which method comprises operating the compressor to exhaust a substantial quantity of non-condensable gases from the low-pressure side of the system to the high-pressure side and venting non-condensable gases from the high-pressure side, admitting a refrigerant charge to the system, providing a container connected to the high-pressure side of the system, transferring from the system to the container the non-condensable gases contained in the system at the time of admitting the refrigerant charge thereto by operating the compressor to effect flow of a mixture of non-condensable gases and refrigerant vapor at substantially condenser pressure into the container and condensing refrigerant vapor in the container, the refrigerant condensed in the container being returned to the system, and isolating the non-condensable gases in the container from the refrigerant charge in the system.

20. The method of charging and removing non-condensable gases from a refrigerating system including a compressor, which method comprises operating the compressor with the high pressure side of the system open to the atmosphere to substantially exhaust the non-condensable gases from the low pressure side of the system, admitting to a container the proper amount only of refrigerant required for a complete refrigerant charge for the system, connecting the container to the system between the condenser and the expansion device at a point where non-condensable gases accumulate, transferring the refrigerant charge from the container to the system, removing from the system the non-condensable gases contained therein at the time of transferring the refrigerant charge into the system by operating a compressor to effect flow of a mixture of non-condensable gases and refrigerant vapor at condenser pressure into the container and condensing refrigerant vapor in the container, the refrigerant condensed in the container being returned to the system, and then isolating the non-condensable gases in the container from the refrigerant charge in the system.

- charge of the system, connecting the container with the refrigerant charge therein to the high pressure side of the system and transferring the refrigerant charge to the system, operating the compressor, concentrating non-condensable gases in a region in communication with the high pressure side of a system by condensing refrigerant vapor from the fluid in said region, and isolating said non-condensable gases from the refrigerant charge in the system.
- 5 21. The method of charging and removing non-condensable gases from a refrigerating system including an evaporator, a compressor, a condenser, and an expansion device, which

method comprises connecting to the system a container containing refrigerant for charging the system, transferring refrigerant from the container to the system, transferring non-condensable gases from the system to the container by operating the compressor to effect flow of a mixture of non-condensable gases and refrigerant vapor into the container, condensing refrigerant vapor in the container, and returning the refrigerant condensed in the container to the system.
